Specification for Design.

Patented Apr. 24, 1917.

Application filed January 31, 1917. Serial No. 145,802. Term of patent 3½ years.

To all whom it may concern:

Be it known that I, GERARDUS POST HERRICK, a citizen of the United States, residing in the city of New York, borough of Manhattan, in the county of New York and State of New York, have invented a new, original, and ornamental Design for a Tread for Rubber Tires, of which the following is a specification, reference being had to the accompanying drawing, forming part thereof.

The figure of the drawing is a plan view

of a portion of a tire showing my new design.

I claim:

The ornamental design for a tread for rubber tire, as shown.

In testimony whereof I have hereunto signed my name in the presence of two subscribing witnesses.

GERARDUS POST HERRICK.

Witnesses:

W. C. MOORE,
JAC. F. REINHARDT.
